SOUND RECORDING METHOD AND
APPARATUS

Homer R. Montague, Washington, D. C.

Application June 27, 1944, Serial No. 542,424

3 Claims. (Cl. 179—100.3)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to the art of sound recording, and particularly to an improved method of making the master record from which disc shaped phonograph records or transcriptions are commonly prepared, usually by the process known as pressing.

In the conventional method of producing masters, a disc of suitable material is placed on a turntable which is rotated at a fixed speed, and a groove is cut into the disc by a cutting head which is caused to travel parallel to a radius. The groove thus produced in the disc is a spiral, the sound energy being utilized to drive the stylus of the cutting head in such a way as to produce a radial modulation of the spiral groove, as is well known in the art. It is well known that any deviation from normal constant speed which occurs in the motion of the turntable produces frequency distortion in the reproduction; various schemes having been employed in order to maintain this speed as constant as possible, with moderate success. None of these schemes, however, is able to maintain the speed sufficiently constant for extremely high fidelity recording.

Another source of difficulty in the making of records or masters by the above described process is the great difficulty in obtaining cutting heads which do not introduce phase and amplitude distortion of the sound energy. This is partly because the mechanical impedance of the cutting mechanism varies with the frequency at which it is driven, as well as with other factors, but there are other reasons for the presence of such types of distortion, all more or less attributable to the presence of mechanical masses in the system.

Accordingly, one object of my invention is to provide a method of and means for producing sound records in which extremely constant recording speed may readily be obtained. Another object is to provide a sound recording system having no moving mechanical parts, and in which distortion attributable to the inertia and impedance of such parts is therefore entirely absent. These and other objects of my invention are obtained by utilizing a stationary sensitized record disc, the sound energy being used to control the position of a beam of cathode rays which normally describes a spiral path adjacent the surface of the disc, and which beam is converted to light which acts photochemically on the disc. Such a disc, when developed photographically, is in fact

2

a sound record itself, capable of being played by a suitable photoelectric phonograph. However, for the production of a master adapted to the process of pressing a plurality of duplicates, I utilize a disc in the form of a photoengraving plate, which, after exposure and development, can be etched to provide a physical sound groove similar to that produced by the conventional cutting process.

10 The accompanying drawings illustrate one embodiment of my invention, in which Fig. 1 is a diagrammatic view of a complete sound recording apparatus in accordance with my invention, while Fig. 2 is a plan view of a sound record produced 15 with this apparatus.

Referring to Fig. 1 of the drawings, 1 designates a cathode ray tube of conventional design, having an evacuated envelope 2, provided at one end with a substantially flat surface 3. This surface 20 is coated with phosphorescent compound as is usual in such tubes. The tube is provided with the usual cathode 4, grid 5, anode 6, horizontal deflecting plates 7, 7' and vertical deflecting plates 8, 8', all as is well known. The cathode 4 is 25 heated in the usual way by current from a transformer or other power source 9, while grid and anode voltages are obtained from any suitable D. C. source.

As stated, the surface 3 is substantially flat. It 30 is more common in cathode ray tube practice to make the viewing end curved, since this construction makes it easier to provide the necessary mechanical strength. In order to maintain a flat disc closely adjacent the envelope, however, I prefer to make the surface 3 flat.

The recording material illustrated is a disc 10 of metal or other suitable material having a coating which is photographically sensitive. This disc is maintained substantially in contact with the flat end 3 of tube 1.

40 In order to cause the beam of cathode rays normally to describe a spiral path over the record material, I may use an oscillator 11 whose output is sinusoidal and of a very low frequency, and the 45 amplitude of which slowly decreases with time. Such oscillators are well known in the art, and the specific means employed to produce the output described is no part of my invention. The output voltage of this oscillator is split into two 50 parts of equal amplitude but differing in phase angle by 90 degrees, by means of a phase splitter diagrammatically shown at 12, the resulting two oscillating voltages being applied respectively to the two pairs of plates 7, 7' and 8, 8'. If the amplitudes of the two sine waves were constant, the 55

path traced by the cathode ray spot on surface 3 would be a circle, since the field causing deflection of the spot is the resultant of the two sine wave voltages applied to the deflection plates.

However, as stated above, the output of oscillator 11 has an amplitude which slowly decreases with time. Hence, the amplitude of each component applied to the deflecting plates also decreases with time, so that the curve traced by the cathode ray spot is actually a close spiral.

In order to produce the desired radial modulation of the sound track, it is merely necessary to introduce the sound energy as an increment or decrement of the output amplitude of oscillator 11. This function I have shown as being performed by the modulator 14, which may be of any of several well-known types. The sound energy to be recorded actuates microphone 15 which is connected to and controls modulator 14, although it is of course possible to control the modulator from other translation devices than microphones.

In order to insure that the scanning process is not started prior to the desired time, a manual control 16 is provided at oscillator 11, operation of which initiates the oscillations and the commencement of the amplitude-decrease (amplitude attenuation) cycle.

In order that the upper frequency range may be faithfully recorded, it is desirable that the cathode ray beam be focused accurately on the plane of the phosphorescent layer, and that the resulting luminous spot be of very small size. It is also desirable to use sensitive material which is very "contrasty," in the photographic sense of the word, since such materials give a very sharp image and tend to minimize the effects of any diffusion which may take place, such as that due to the size of the particles in the phosphor on the face 3 of tube 1.

In the event that the radius of disc 10 is so large compared to the distance from surface 3 to the virtual source of the cathode rays that it is difficult to keep the beam in focus for all values of radial deflection required, the focus may be corrected automatically by adjusting the voltage on grid 5 in accordance with the amplitude attenuation controlling the radius of the trace. This may be done, for example, by applying a voltage obtained from the attenuating means to the anode of the tube 1, in addition to its normal potential, as illustrated diagrammatically by the connection 20 in Fig. 1.

After the recording process has been completed, the record disc 10 is removed, developed photographically, and etched in a manner well known in the art of photoengraving. The etching process is preferably chosen so as to leave the groove edges with a polished surface, in order to reduce the surface noise which would otherwise be produced in pressings made therefrom.

It will be observed that my process produces directly a metal master suitable for use in producing stereotype negative matrices in the usual way, that is, by electroplating the master and stripping off the plated layer. However, it is unnecessary to render my master record electrically conducting prior to plating, since the original metal plate is itself an excellent conductor.

In the event that a very high polish is desired in the groove of a master prepared according to my invention, exceeding that obtained with the best available etching solutions, the master may be subjected to any of several well-known electrolytic polishing techniques. These may, if desired, be applied prior to the removal of the re-

sist which remains on the unrecorded portions of disc 10 after the etching process. Such a polishing step is desirable where pressings especially free from background noise are required.

It is obvious that a record disc 10 produced in accordance with my invention can be played back directly on a conventional phonograph instead of, or in addition to, being used as a master for the production of matrices as used in the pressing process. Being of metal, my original record is of course a great deal harder and more rugged than materials ordinarily used for this purpose. In fact, one of the advantages of my process is that the master may be played back directly for checking purposes prior to the making of matrices and pressings therefrom, without the loss of quality that occurs when ordinary cutting materials are played even once prior to the making of the matrices.

The frequency of oscillator 11 and the rate of amplitude attenuation of its output depend upon the speed at which it is desired to reproduce the record and the desired pitch of the spiral. For example, to produce a record for playing at 78.26 revolutions per minute (a standard speed for conventional phonographs), a frequency of $3\frac{1}{2}$ cycles per second is required, since one complete cycle represents one complete revolution of the cathode ray spot on disc 10, and since

$$30 \quad 78.26 \div 60 = 30 \div 23$$

very closely. If it is desired that the average pitch of the spiral groove be 112 lines per inch, which is a widely used standard, then the rate of amplitude attenuation of the output of oscillator 11 must be such that after 112 cycles of the output of oscillator 11, corresponding to 112 revolutions of the cathode ray trace, the amplitude will drop $1/V$ volts, where V is the voltage sensitivity of the cathode ray tube in inches per volt.

It will be observed that the constancy of the angular velocity of the cathode ray trace on record 10 depends only upon the constancy of the frequency of the oscillator 11, and not upon the linearity of its amplitude attenuation. Exceedingly constant speed may be obtained with ordinary types of oscillators such as piezo-electric or magnetostriction oscillators, with suitable frequency dividers to reduce the frequency to the desired value. Since the rate of amplitude attenuation is not particularly critical, such attenuation may be produced, if desired, by a variable potentiometer driven by a low-power motor such as a small synchronous motor operated from the power mains. However, I have found that it is perfectly feasible to perform this function by a decay circuit incorporated in the oscillator itself.

My invention is obviously subject to many refinements that will occur to those skilled in the art. For example, a manual or automatic amplitude attenuating device may be interposed between oscillator 11 and phase splitter 12, for rapidly changing the radius of the curve traced on disc 10. Such an arrangement would permit the production of the relatively high pitch starting and stopping grooves found on many recordings produced with conventional recorders.

I claim:

70 1. In a sound recording system, a cathode ray tube, means for supporting a sensitive record blank in a stationary position adjacent said tube, means for causing the luminous spot produced by said tube to trace a non-repetitious spiral path over a blank supported by said supporting means,

and means for modulating the motion of said beam, orthogonally to the general direction of movement of said beam, in accordance with the sound energy to be recorded.

2. In sound recording apparatus, the combination with a cathode ray tube provided with means for deflecting the cathode ray beam in two directions at right angles to one another, of a constant frequency oscillator, means for dividing the output of said oscillator into two components of equal amplitude and differing in phase by 90°, means for applying said two components to the deflecting means of said tube, means for varying the amplitude of the output of said oscillator slowly in a substantially uniform manner whereby the trace of said tube becomes a closely spaced, non-repetitious, multi-turn spiral, and means connected to said oscillator and said tube for simultaneously varying both of said components equally in amplitude in accordance with sound to be recorded, whereby a radial modulation of said spiral trace is accomplished, and means for holding a sensitive record blank in position to be impinged upon by the trace of said tube.

3. The method of making a disc-shaped sound record comprising providing a disc of photosensitive material, producing a narrow beam of cathode rays, deflecting said beam electrically so as to trace a non-repeating closely-spaced, multi-turn spiral of substantial length upon the surface of said disc, modulating the position of said beam orthogonally to the general direction of said spiral at a rate corresponding to the frequency

of sounds to be recorded and at an amplitude sufficiently small to prevent overlap between adjacent turns of said spiral, converting at least a portion of the energy of said beam into photographically actinic light prior to its impingement upon said surface, and thereafter developing said surface.
